UNITED STATES PATENT OFFICE.

WILLIAM J. KEARNEY, OF DES MOINES, IOWA.

PLIERS.

1,271,911.

Specification of Letters Patent.

Patented July 9, 1918.

Application filed August 13, 1917. Serial No. 185,932.

To all whom it may concern:

Be it known that I, WILLIAM J. KEARNEY, a citizen of the United States, and resident of Des Moines, in the county of Polk and State of Iowa, have invented certain new and useful Pliers of which the following is a specification.

The object of my invention is to provide a tool of the general type of a pair of pliers, having pivoted, relatively movable jaw members which may be readily and easily set in any position of their adjustment, whereby the device may be made to serve as a wrench.

15 A further object is to provide such a device having parts so constructed and arranged that the pressure of the handles toward each other serves to lock the jaw members in their then position, and also so arranged that upon the release of the handles the jaw members will be automatically unlocked.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of a pair of pliers embodying my invention.

Fig. 2 shows a side elevation of the same.

Fig. 3 shows a detail view of the ratchet pin device, and

Fig. 4 shows a sectional view, taken on the line 4—4 of Fig. 1.

In the accompanying drawings I have used the reference numerals 10 and 11 to indicate the jaws of my improved tool, which may be of any desirable size and shape. The jaw 10 is preferably formed integral with a handle 12, and is provided with an angular opening 13 extending through it.

45 The jaw 11 is pivotally connected at 14 with a handle 15. The jaw 11 is provided with an opening 16, forming a bearing and having an enlarged portion 17 to receive the ratchet hereinafter mentioned.

I provide a ratchet pin device comprising a ratchet wheel 18 received in the opening 17, as shown in Fig. 4. Formed on the ratchet 18 is a cylindrical extension 19 received in the opening 16. Extending away

from the extension 19 is an angular shaft member 20 received in the opening 13. It will be seen that on account of the angular shape of the member 20 and the opening 13, the ratchet 18 will be caused to move according to the movement of the jaw 10 and handle 12. The free end of the squared shaft 20 may be provided with a head 21 or other means for retaining the ratchet in position.

The jaw 11 is provided with an opening 22 leading from the opening 17 to the end of the jaw 11 adjacent to the handle 15. The opening 22 is provided near its middle with an enlarged portion 23 which extends to the top of the jaw 11. Received in the opening 22 is a pawl 24, one end of which is designed to coact with the ratchet 18. The pawl 24 is provided with an upwardly projecting pin 25.

Mounted on the pawl 24 between the pin 25 and the shoulder formed by the forward end of the enlarged portion 23 of the opening 22, is a coil spring 26 which normally holds the pawl 24 out of engagement with the ratchet 18. What I shall call the rear end of the pawl 24, which is the end adjacent to the handle member 15, is normally held by the spring 26 in position projecting beyond the jaw member 11 toward the handle 15.

85 In the practical use of my improved pliers where it is desired to use the tool as a wrench, the handle 15 is held rigidly in position and the handle 12 is moved away therefrom, thereby opening the jaws 10 and 11 until they are in their proper relative positions for use as a wrench. Thereupon the handles 12 and 15 are drawn toward each other. The movement of the handle 15 toward the handle 12 presses the pawl 24 toward and into engagement with the ratchet 18, and as long as the handles 12 and 15 are held pressed toward each other the jaws 11 and 10 will be locked in their relative positions and can be used as a 100 wrench.

When it is desired to release the jaws, all that is necessary is to release the handle 15, whereupon the spring 26 will tend to move the handle 15 away from the handle 12 and to release the jaw members from their locked relation.

Some changes may be made in the construction and arrangement of the various parts of my improved pliers without de-

parting from the essential features and purposes of my invention, and it is my intention to cover by this application any modified forms of structure or use of mechanical equivalents which may be included within the scope of the claims of the patent to be issued upon this application.

I claim as my invention:

1. In a device of the class described, a pair of pivoted jaw members, handles thereon, and means whereby the movement of said handles toward each other, when the jaws are gripped on an object, locks said jaws in their then relative positions so that so long as the handles are gripped and held against movement away from each other the jaws cannot be moved farther together when they are on or removed from such an object.
2. In a device of the class described, a pair of jaw members, a ratchet device on one of said jaw members pivotally mounted in the other jaw member, a handle on one of said jaw members, a handle pivotally mounted on the other jaw member, a pawl carried by said other jaw member, and yielding means for holding said pawl out of engagement with said ratchet, the parts being so arranged that when said pivoted handle is moved toward the other handle it engages said pawl and when said jaw members are gripped on a fixed object forces said pawl into engagement with said ratchet, whereby so long as the handles are pressed toward each other, the jaw members are

locked against movement toward each other whether off or on such an object.

3. In a device of the class described, a pair of jaws, a ratchet device pivoted in one jaw and fixed with relation to the other jaw, a pawl carried by said first jaw, yielding means for normally holding said pawl out of engagement with said ratchet, a handle fixed on said second jaw, and a handle pivoted to said first jaw and adapted when moved toward said second jaw to engage said pawl and move it into engagement with said ratchet.

4. A pair of pliers comprising a pair of jaws, an angular shaft mounted in one of said jaws having a cylindrical portion mounted in the other of said jaws and having on one end a ratchet, a handle on the jaw which receives the angular shaft, a handle pivoted to the other jaw at a point on the opposite side of its pivotal point from its gripping member, a pawl slidably mounted in the last described jaw adapted to coact with said ratchet, and with said pivoted handle, and a spring adapted to hold said pawl away from said ratchet, the parts being so arranged that when the pivoted handle is moved toward the other handle it will engage said pawl and force it into engagement with said ratchet for thereby locking said jaws against relative movement.

Des Moines, Iowa, August 10, 1917.

WILLIAM J. KEARNEY.
